SHEET METAL STRETCHING VISE

William J. Desjarlais, Sergeant Bluff, and Herman E. La Fleur, Sioux City, Iowa, assignors of five per cent to J. Allen Orr, Sioux City, Iowa

Application April 19, 1948, Serial No. 21,797

8 Claims. (Cl. 81—15)

1

This invention relates to an improvement in sheet metal stretching vises and is particularly adapted to be used in the straightening of badly damaged doors and particularly those of automobile doors which have become bent or damaged due to collision or other accident.

Another object of the invention is to provide a device that will relieve the pressure from the door exerted by the bent portions therein in order to facilitate the return of such doors to their original shapes when straightened by application of a mallet or hammer.

Another object of the invention is to grip and stretch the door as much as is possible while the straightening operation is taking place.

And another object of the invention is to provide a tool which will absorb the pressure normally incurred when a highly resistant object is being straightened.

A further object of the invention is to provide means that are adjustable to accommodate various sizes of doors or other material to be straightened.

Other objects and advantages will become apparent during the course of the following description.

In the accompanying drawings, forming a part of this specification, wherein like characters of reference denote like parts throughout:

Figure 1 is a perspective view of the invention as applied to a bent door;

Figure 2 is a side elevation of the improved tool, with certain parts being shown in section;

Figure 3 is a transverse vertical view taken substantially on line 3—3 of Figure 2, and

Figure 4 is a transverse vertical sectional view, taken substantially on the line 4—4 of Figure 2, as seen in a direction opposite that of Figure 3.

The difficulty occurring in straightening badly bent doors of highly resistant material appears to be due to the fact that the pressure exerted by the bend in the door resists the efforts of a hammer or other tool used to straighten out such hump. In order to overcome this objection, it would appear to be desirable that pressure exerted by the door be relieved so that there will be considerably less resistance to the hammering effect during the straightening process. In order to achieve these ends, the instant invention has been devised.

Referring to Figure 1, the tool of the invention is indicated generally by numeral 10 and is shown engaging the end of a door or other damaged object 12.

As is best illustrated in Figure 2, the tool con-

2

sists of a sectional housing 14 and 16. It is to be noted that housing member 14 is tubular and of considerably greater length than housing 16. Housing 14 is hollow in construction and is open at each end. A suitable bushing 18 threadedly bored along the axial length thereof, is welded or otherwise suitably mounted on the outer extremity of housing member 14. Housing section 16 is open at one end thereof and is closed at the outer extremity by means of a suitable plug 22 welded therein. Housing member 16 is a sleeve and hollow in construction in the manner of housing 14. A screw shaft 24 is rotatably seated within bushing 18 and extends into housing 14 for a short distance. A suitable actuating crank handle 26 is secured to screw 24 for actuation thereof. Secured to the inner end of actuating screw 24 is an elongated steel shaft 28, shaft 28 being of a diameter closely fitting the inner periphery of housings 14 and 16 and extends through both housings 14 and 16 as is clearly illustrated. It will thus be seen that the shaft 28 and the housing 16 considered together constitute a member slidably received within and extensible from the tubular housing 14.

Mounted on housing members 14 and 16 are clamps 30. Two clamps are used, and as they are identical in construction, a description of one will be applicable for the other. As is best illustrated in Figures 2 through 4, clamp 30 is of two separate members 32 and 34 arcuately grooved on the inner surfaces thereof and in complementary relation at 36 for retention in non-slipping relation on the respective housing pipes. Clamp members or jaws 32 and 34 are retained in locked position by threaded bolts 38 extending through suitable bores therein. Bolts 38 include headed stops 40 on one end thereof and mount on the opposite extending end a clamping plate or bar 42. Door 12 is adapted to be placed between plate 42 and the adjacent surface of jaw member 32 and is gripped by suitable teeth 44 mounted in opposed relation on the facing surfaces of plate 42 and jaw 32, teeth 44 being retained in position by bolts 46.

In use, the ends of a suitable object such as an automobile door are inserted between plate 42 and jaw 32, the teeth 44 or the ends thereof gripping the outer extremities of door 12. Bolts 38 are then rotated to insure non-slip engagement with the door while the stretching operation takes place. When crank 26 is rotated, screw 24 travels in bushing 18 until steel shaft 28, extending therefrom, abuts plug 22 or housing 16. Continued rotation of crank 26 in the same direction, pro-

duces further separation of the housing members with the attendant stretching longitudinally of door member 12. Plug 22 absorbs the pressure on shaft 28 by screw 24 and the bent portions of the door are then readily hammered straight.

When door 12 is to be released, rotation of crank 26 is reversed, and the door is released from engagement by plate 42 and member 32. One of the clamps 30, preferably the one on housing 14, is slidably adjusted to accommodate different sizes of objects to be straightened.

While a preferred embodiment of the invention has been shown and described, it is to be understood that various changes in size, shape and arrangement of parts may be made without departing from the spirit of the invention or the scope of the appended claims.

Having described the invention what is claimed as new is:

1. A tool comprising an elongated tubular member and an elongated member slidably received within and extending axially from the tubular member, a pair of vises, means for adjustably positioning and securing one of said vises on the tubular member, means for adjustably positioning and mounting the other vise on the second mentioned member, and means for urging relative axial movement of said members.

2. A tool comprising an elongated tubular member and an elongated member slidably received within and extending axially from the tubular member, a pair of vises, means for adjustably positioning and securing one of said vises on the tubular member, means for adjustably positioning and mounting the other vise on the second mentioned member, and means for urging relative axial movement of said members, said vises including means responsive to actuation of said first means and the second means for clamping work.

3. A tool comprising an elongated tubular member and an elongated member slidably received within and extending axially from the tubular member, means urging extension of the elongated member from the tubular member, a pair of vises one of which is mounted on the tubular member and the other of which is mounted on the second mentioned member, each of said vises comprising a pair of clamping plates and a gripping plate, one of said members being disposed between the clamping plates, securing means extending through all of said plates for urging them towards each other, whereby a work may be gripped between one of the clamping plates and the gripping plate simultaneously with the clamping plates being urged towards said one member by the securing means.

4. A straightening tool for body and fender repair work comprising a jack including a pair of axially aligned extensible housing sections, means for causing relative axial movement of the sections, a combined jaw and clamp construction adjustably positioned on each of said sections, said construction comprising a pair of spaced clamping members, the clamping members receiving one of the sections therebetween and having their adjacent faces substantially complementary to the surface of the section engaged thereby, a gripping plate disposed on the side of one of the members, said members and the gripping plate having aligned apertures therethrough, and adjustable securing means extending through the apertures to urge the members towards each other to clamp the section therebetween and also to urge the gripping plate

towards the members to grip an object between the gripping plate and said one of the clamping members.

5. For use with a straightening tool for body and fender repair work including an extensible jack having a pair of aligned sections; a combined jaw and clamp construction adapted to be adjustably positioned and clamped to the sections comprising a pair of spaced first and second clamping members for receiving a section therebetween, the adjacent surfaces of the clamping members having surfaces adapted to be substantially complementary to a jack section, a gripping plate disposed on the side of the first of said members opposite the second member, said clamping members and the gripping plate having aligned apertures therethrough, and adjustable securing means extending through all of the apertures for urging the clamping members towards each other to clamp a jack section therebetween and also for urging the gripping plate towards the first clamping member to grip an object placed between the plate and the first clamping member.

6. The combination of claim 5, wherein the adjacent surfaces of the gripping plate and said first member are serrated for snug frictional engagement with an object gripped therebetween.

7. A tool consisting of a two part housing, a clamp adjustably mounted on each of the housing parts, work engaging means carried by said clamps, means extending through the two part housing for movement of the housing parts towards and away from each other, each of said clamps comprise grooved jaws, securing means extending through said jaws, said work engaging means including a gripping plate engaged by said securing means, so that when the securing means are tightened, the clamps are immovably retained on the housing and one of said clamp jaws and said plate tightly retains a work therebetween.

8. The combination of claim 1, wherein said second mentioned means includes a sleeve rotatably mounted on the second mentioned member, and means for limiting axial movement of the sleeve on the second mentioned member.
